CLAIM

The ornamental design for an inflatable mattress, as shown and described.

DESCRIPTION

FIG. 1 is a perspective view of an inflatable mattress showing our new design;

FIG. 2 is a front view thereof;

FIG. 3 is a back view thereof;

FIG. 4 is a left view thereof;

FIG. 5 is a right view thereof;

FIG. 6 is a top view thereof;

FIG. 7 is a bottom view thereof;

FIG. 8 is an enlarged view of the encircled area 8 of FIG. 1;

FIG. 9 is an enlarged view of the encircled area 9 of FIG. 2;

FIG. 10 is an enlarged view of the encircled area 10 of FIG. 4; and,

FIG. 11 is an enlarged view of the encircled area 11 of FIG. 7.

The broken lines shown in the figures depict portions of the Inflatable mattress that do not form part of the claimed design. In FIGS. 1, 2, 4 and 7–11, the broken lines depict the enlarged view boundaries that do not form part of the claimed design.

1 Claim, 9 Drawing Sheets
